UNITED STATES PATENT OFFICE.

CURRAN E. MITCHELL, OF FORT PAYNE, ALABAMA.

WASHING-MACHINE.

No. 823,887.

Specification of Letters Patent.

Patented June 19, 1906.

Application filed June 24, 1904. Serial No. 213,996.

To all whom it may concern:

Be it known that I, CURRAN E. MITCHELL, a citizen of the United States, residing at Fort Payne, in the county of Dekalb and State of Alabama, have invented new and useful Improvements in Washing-Machines, of which the following is a specification.

This invention relates to washing-machines of that class having a rotary clothes-holding drum, with coöperating rollers disposed in yielding relation thereto, and the purpose of the same is to improve machines of this class and facilitate cleansing clothing, fabrics generally, wool, feathers, and other articles by a positive arrangement in a receptacle or suds-box of a slatted drum and rotatable rollers in opposition thereagainst, presenting a plurality of rigid angular edges to the articles or materials on the drum, one of the rollers being composed of a series of members spaced apart to form circumferential channels or grooves to permit a rapid flow back of the suds or water through the said roller and also materially increase the number of angular edges in contact with the articles on the drum.

The machine also contemplates the provision of a receptacle or suds-box having a cover movably attached to one end and supplied with folding legs to adapt said cover to be used as a receptacle for the clothing or other articles to be or that have been cleansed.

A further aim is to provide a washing-machine having a comparatively small number of simple, strong, and durable contributing elements which can be quickly assembled and disassociated.

In the drawings, Figure 1 is a longitudinal vertical section of a washing-machine embodying the features of the invention and showing the cover thrown back in full lines and closed in dotted lines. Fig. 2 is a top plan of the machine with the cover open and partially broken away. Fig. 3 is a detail perspective view of one of the rollers. Fig. 4 is a detail perspective view of one of the supporting-frames carrying one of the rollers, the frame being broken away in part to show the pivotal connection. Fig. 5 is a detail view in end elevation of the drum.

Similar numerals of reference are employed to indicate corresponding parts in the several views.

55 The numeral 1 designates a receptacle or suds-box having legs 2 and at a suitable

point may be provided with a drain device. This receptacle or suds-box will be constructed in the most approved manner to render it water-tight and also, preferably, composed of wood or some other non-corrosive material. Thereover is removably applied a cover or inclosure 3, connected at one end by loose hinge devices, which in the present instance consist of upturned hook members 4, secured to the cover end and loosely and separably engaging angular arms 5, attached to the end of the receptacle or suds-box near the top of the latter. The top of the cover 3 has a rod 6 extending transversely thereacross, and on the ends of the rod close to the opposite sides of the cover legs 7 are movably applied. This cover, as shown by Fig. 1, is adapted to be thrown over to form a receptacle or holding means for articles of clothing to be washed or cleansed, and during such arrangement or use the top of the cover becomes the bottom and the legs 7 are turned down to engage the base-support for the machine. When the cover is over the top of the receptacle or suds-box 1, the legs 7 are reversed and depend over the sides of the cover.

The sides of the receptacle or box 1 have bearing-grooves 8 formed in the centers of the upper edges thereof in transverse alignment, said grooves also partially extending through wear or bearing plates 9, preferably countersunk in the sides of the receptacle. In the grooves 8 and engaging the upper edges of the wear or bearing plates 9 are the reduced terminals of a shaft or axle 10, extending centrally through a clothes-drum 11, having end spiders 12 with center-reinforcing plates 12^a, the spiders being connected to annular heads 13, having inwardly-projecting circumferential flanges or rims 14, one on each, to which are secured the terminals of slats 15. The slats 15 are spaced apart from each other to form water circulating openings, and this structure, together with the open heads, permits free passage of water through the drum both transversely and longitudinally and, in fact, in all directions. The annular heads 13 project outwardly beyond the outer surfaces of the slats 15 to produce guards 16 for opposite rollers 17 and 18. The rollers are held in close contact with the slats of the drum and the ends thereof engage the guards 16. The rollers are also formed with a plurality of angular edges which efficiently serve to work out or remove

the dirt from the clothing or other articles placed on the drum to be cleansed. The roller 18 is polygonal in cross-section, and the roller 17 is made up of a plurality of polygonal members or disks 19, regularly spaced apart by interposed space-sleeves 20 to form a series of channels which permit the water flowing back over this roller to pass downwardly into the receptacle or suds-box 1 with greater rapidity. In addition the members or polygonal disks 19 present an increased number of angular edges to the fabrics or articles of clothing or the like on the drum and expedite the operation, the fabrics in some instances being pressed in between the members or disks with advantage in the cleansing operation without liability of injury to the material washed. The space-sleeves 20 are secured to the several members or disks 19 to cause the latter to unitedly rotate on the spindle 21, carrying the roller. The roller 18 has terminal trunnions 22, which rotate therewith, and the spindle 21 and trunnions 22 of the respective rollers are loosely mounted in the upper terminals of supporting-frames consisting of side bars or arms 23, having lower slots 23^a, opening through the inner edges and removably engaging pivot-studs 23^b on the inner 25 opposing sides of the receptacle or suds-box, the arms being connected by cross-bars 24 above their lower pivotal ends. The cross-bar of each supporting-frame has outwardly-projecting studs 25 near the ends thereof, over which are fitted the inner extremities of pressure-springs 26, having their outer ends seated in sockets 27 in the ends of the receptacle or suds-box 1. The ends of the cross-bars 24 are pivotally held in the arms 30 23, as shown by Fig. 4, to compensate for the change of angle of the supporting-frames and maintain the springs 26 in such position with respect to the parts they engage that disengagement thereof will be obviated and the 35 most effective spring-pressure will result. By means of the springs the supporting-frames and the rollers carried thereby are forced over into close engagement with the drum, but with such yielding pressure as to 40 permit the clothes or other articles placed on the drum to be forced between the rollers and the surface of the drum without injury to the clothes. The supporting-frames for the rollers do not in the least interfere or contact with any part of the drum, and the inner 45 opposing edges of the side arms 23 are longitudinally concaved, as at 28, to insure a clearance thereof with respect to the peripheries of the annular heads 13 adjacent to 50 which they are normally held. The supporting-frames can be readily withdrawn from the suds-box for cleaning purposes and afterward easily reset in operative position, and, further, the parts of the supporting-frames are assembled and held intact when

in the suds-box with the use of fastenings, thereby rendering it possible to quickly disjoint the frames, if desired.

At diametrically opposite points the drum has bracing-slats 29, which are wider than the remaining slats, and adjacent to each is a 55 slideable locking-slat 30, having its ends freely movable on the circumferential flanges or rims 14 and its inner side connected to the corresponding side of the slat 29 by coil-springs 31, which tend to bring the one edge of the locking-slat in each instance normally in close relation to the adjacent edge of the bracing-slat 29. The springs 31 are of such tension as not only to normally draw the locking-slats 30 in close relation to the bracing-slats 29, but also hold the terminals of the said locking-slats in close bearing relation to the circumferential flanges or rims 14. For convenience in operating or moving the 60 locking-slats they are formed with recesses 32 at their centers. By having these locking or holding slats at opposite parts of the drum clothing or other articles may be more conveniently attached without delay or without requiring a tedious expenditure of time to locate the locking or holding slats, as would be the case in the use of a single locking or holding slat.

One reduced terminal of the shaft or axle 65 of the drum has a crank 33 secured thereon for rotating the drum within the receptacle or suds-box between the rollers, and at any time desired the drum may be withdrawn from the suds-box to cleanse the latter or for other purposes, and to normally hold the said drum in the suds-box hook-catches 34 are 70 movably attached to the wear or bearing plates 9 and are thrown over the opposite reduced terminals of the shaft or axle of the 75 drum. At any time found necessary these hook-catches are disengaged from the terminals of the drum shaft or axle and the drum withdrawn from the suds-box or receptacle.

In the operation of the machine articles of 80 clothing, fabrics, or other materials are applied to the drum and terminally inserted between either one of the locking-slats 30 and the adjacent bearing-slat 29. The drum is then rotated, and the article of clothing or 85 fabric or other material having length will be wound around the drum in close contact with the slats 15. The repeated engagement of the rollers 17 and 18 with the article or material held on the drum will result in a thorough 90 cleansing operation. The quantity of suds or wash-water disposed in the receptacle or box 1 may be varied, and during the washing 95 operation it will flow through the drum and come in contact with the opposite sides of the 100 fabric or article washed. When the cover 3 is closed over the receptacle or box 1, the steam will beneficially act on the article or material washed. Furthermore, in the actuation 105 of the drum rotation in opposite direc- 110

tions may be imparted thereto to thoroughly cleanse the article of clothing or fabric thereon, and it will be understood that a reversal of the drum after movement thereof in one direction will cause the article or fabric to unwind from the drum and then rewind on the latter, thereby bringing opposite sides of the article cleansed in close engagement with the rollers.

10 Changes in the proportions, dimensions, and minor details may be resorted to without departing from the spirit of the invention.

Having thus fully described the invention, what I claim as new is—

15 1. In a washing-machine, a receptacle, a drum rotatably mounted in the receptacle, supporting-frames removably pivoted adjacent to opposite ends of the receptacle and having pivoted cross-bars, rollers mounted 20 in the upper extremities of the frames, and springs interposed between the cross-bars and the ends of the receptacle.

25 2. In a washing-machine, a receptacle, a drum rotatably and removably mounted in the receptacle, supporting-frames remov-

ably pivoted in the receptacle adjacent to opposite ends of the latter and having pivoted cross-bars with outwardly-projecting studs, springs engaging the said studs and the ends of the receptacle, and rollers mounted in the 30 upper extremities of the frames and normally held in engagement with opposite portions of the drum.

3. In a washing-machine, a receptacle, a drum rotatably mounted in the receptacle, 35 supporting-frames pivotally disposed in the receptacle adjacent to opposite portions of the latter, and having intermediate movable elements, rollers held by the upper extremities of the frames, and springs engaging the 40 intermediate movable elements of the frames and the ends of the receptacle to force the rollers into normal contact with the drum.

In testimony whereof I have hereunto set my hand in presence of two subscribing witnesses. 45
